UNITED STATES PATENT OFFICE.

DAVID T. MAY, OF NEW YORK, N. Y., ASSIGNOR TO WESTERN ELECTRIC COMPANY,
INCORPORATED, OF NEW YORK, N. Y., A CORPORATION OF NEW YORK.

VACUUM LIGHTNING-ARRESTER.

1,244,528.

Specification of Letters Patent. Patented Oct. 30, 1917.

Application filed November 9, 1916. Serial No. 130,349.

To all whom it may concern:

Be it known that I, DAVID T. MAY, a citizen of the United States, residing at New York, in the county of New York and State 5 of New York, have invented certain new and useful Improvements in Vacuum Lightning-Arresters, of which the following is a full, clear, concise, and exact description.

This invention relates to protective devices, and is particularly useful in connection 10 with vacuum lightning arresters.

The voltage, at which a spark will be struck between the electrodes of a vacuum lightning arrester, and thus give protection 15 to the apparatus on the line, is determined by the distance of separation of the electrodes and the degree of vacuum in the arrester. However, when the vacuum is destroyed and the pressure increased to that 20 of the atmosphere, the sparking voltage will be too high for satisfactory protection of the apparatus. It is, therefore, desirable from the standpoint of protection to have means for short-circuiting the arrester, that 25 is, establishing a conducting path of low resistance in parallel to the spark gap, if the evacuated container leaks and allows the pressure within it to increase to that of the atmosphere. A short-circuited arrester can 30 be detected by well-known line tests and a new one put in its place.

The present invention is characterized by the employment of deliquescent material which normally separates short-circuiting 35 contact members which tend to engage one another. When the deliquescent material is softened by absorption of moisture carried into the evacuated container by the air when the vacuum fails, it permits the short- 40 circuiting contact members to engage one another.

The drawing shows a vacuum lightning arrester having the present invention embodied therein, a portion of the container 45 being broken away and certain parts being shown in cross-section.

The vacuum lightning arrester herein- 50 illustrated is of the general type fully described in a United States application for patent in my name, Serial No. 101,747, filed June 5, 1916, and assigned to the same assignee as the present case. The arrester comprises an evacuated glass container 1, mounted upon a base 2. Within the container 55 1 is a hollow glass stem 3, upon which

concentric cylindrical electrodes are supported. Electrical connection with the electrodes is obtained through leading-in wires 4 and 5, which are led from the base 2 through the stem 3 and are connected to the 60 electrodes by means of screws 6 and 7.

Secured to the electrodes by screws 6 and 7 are spring members 8 and 9 which are preferably made of flat pieces of brass or other conducting material. These spring 65 members are bent in a manner suitable for holding the short-circuiting device between their upper ends, substantially as shown in the drawing.

The short-circuiting device herein illustrated comprises a container consisting of tubes 10 and 11 which are preferably made of some non-conducting material such as glass. Tube 10 has a large bore 12, while tube 11 has a small bore 13 with an enlarged 75 portion 14, at its inner end. A stationary contact member 15 is carried in tube 11 and projects through the outer end, being connected to a suitable terminal 16, which is cemented to the tube 11 and through which 80 electrical contact is made with the spring member 8. The tube 10 contains a movable contact member in the shape of a helical spring 17, one end of which projects through tube 10 and is connected to terminal 18 engaged by the spring member 9. The other end of the spring 17 is straight and engages under compression a disk or pellet of deliquescent material 19 placed in the enlarged 85 portion 14 of tube 11. The tubes are sealed 90 together on the line 20. A small aperture 21 is cut in tube 10 in order that the pressure in the arrester and within tubes 10 and 11 may always be the same. In order to prevent the 95 deliquescent material from absorbing moisture from the air and thus operating the device between the time of its assembly and the time of exhausting and sealing the arrester, aperture 21 is sealed with a low temperature melting wax 22 such as paraffin. This wax 100 can readily be melted during the exhausting operation, leaving the aperture open. Means is provided for taking up the melted wax, consisting of a piece of slotted blotting paper 105 23 surrounding the wax and held by spring 24 clips 24. This arrangement not only prevents the melted wax from falling on the parts below, but insures the removal of the wax from the aperture.

As long as the arrester remains in its 110

evacuated condition the pellet 19 of deliquescent material will remain hard and will separate the stationary contact member 15 and the movable contact member 17. If, 5 however, the arrester leaks and permits air to enter, the moisture carried in with the air will soften the pellet 19 and permit it to be pierced by the prolonged end of helical spring 17, which is under compression, thus 10 making electrical contact with contact member 15 and completing the short circuit between the electrodes.

The description of the invention is herein confined to one form of short-circuiting device 15 for use with a certain construction of vacuum protective device. It will be readily understood, however, that the invention may be embodied in many other forms and used in connection with practically all types of 20 vacuum protective devices.

What is claimed is:

1. In a vacuum lightning arrester, a short-circuiting device comprising contact members tending to engage one another, and means 25 comprising deliquescent material normally retaining said members separated.
2. In a vacuum lightning arrester, a short-circuiting device comprising contact members tending to engage one another, and deliquescent material normally separating said contact members.
3. In a vacuum lightning arrester, a short-circuiting device comprising a fixed contact member, a movable contact member tending 35 to engage said fixed member, and deliquescent material normally preventing said mov-

able contact member from engaging said fixed contact member.

4. In a vacuum lightning arrester, a short-circuiting device comprising a container of 40 non-conducting material, a fixed contact member located in one end of said container and projecting therefrom, a movable contact member located in the other end of said container and projecting therefrom and 45 tending to engage said fixed contact member, and a deliquescent material located between said contact members and normally preventing their engagement.

5. In a vacuum lightning arrester, a short-circuiting device comprising a container, a 50 fixed contact member located in one end of said container and projecting therefrom, a movable contact member located in the other end of said container and projecting there- 55 from and tending to engage said fixed contact member, a deliquescent material located between said contact members and normally preventing their engagement, terminals to which said projections of said contact mem- 60 bers are connected, and spring metallic mem- bers bearing against said terminals and firmly holding said short-circuiting device between their ends, the other ends of said 65 spring metallic members being connected to the electrodes of said vacuum lightning ar- rester.

In witness whereof, I hereunto subscribe my name this 8th day of November A. D. 1916.

DAVID T. MAY.
